UNITED STATES PATENT OFFICE.

GEORGE FRANK GOSS, OF WALLACETON, PENNSYLVANIA, AND JOHN E. PARKER, OF WASHINGTON, DISTRICT OF COLUMBIA; SAID PARKER ASSIGNOR TO SAID GOSS.

GAME-REGISTER.

No. 813,551.

Specification of Letters Patent.

Patented Feb. 27, 1906.

Application filed May 27, 1904. Serial No. 210,101.

To all whom it may concern:

Be it known that we, GEORGE FRANK GOSS, residing at Wallaceton, in the county of Clearfield and State of Pennsylvania, and JOHN E. PARKER, residing at Washington, District of Columbia, citizens of the United States, have invented a new and useful Game-Register, of which the following is a specification.

This invention relates to game-recorders, and has for its principal object to provide a means whereby a printed record may be kept of the number of games played on a pool-table or similar table where movable objects, such as balls, are forced into receiving-pockets.

A further object of the invention is to construct a device of this character in which the number of balls pocketed by each player will be automatically recorded, the balls of each player being recorded in a separate column, so that at the end of the game there will be no difficulty in determining the winner or the loser.

A still further object of the invention is to construct a device of this character in which a record-strip and its recording devices are so arranged and constructed as to permit the writing of the initials or names of the players in their respective columns before the starting or after the completion of the game.

A still further object of the invention is to provide a device of this character in which the amount due for the game shall be printed at the completion of each game.

A still further object is to provide a registering device in which the record-strip is provided with separate columns in which are imprinted the number of balls made by each player, and at the end of the game the amount due is printed automatically in that column in which the lowest number of balls have been recorded.

A still further object of the invention is to provide a pool-table recording device in which a printed record of the games and amount due is made on a record-strip which may be utilized as a bill to be paid at the end of the game or at the end of a series of games.

A still further object of the invention is to provide a self-recording register in connection with a ball-receptacle into which the balls automatically roll from the several pockets

and in which it will be impossible to remove the receptacle in order to replace the balls on the table without making a printed record of the fact on the recording-strip.

With these and other objects in view, as will more fully hereinafter appear, the invention consists in the novel construction and arrangement of parts, hereinafter fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a longitudinal sectional elevation of a pool-table provided with a ball-receptacle to be connected to a game-register in accordance with the invention. Fig. 2 is an elevation looking at one end of the table and showing the arrangement of the ball-receptacles and the circuit-closers. Fig. 3 is a detail sectional view of a portion of the same on the line 3-3 of Fig. 2. Fig. 4 is an elevation of the game-register constructed in accordance with the invention, a portion of the casing being broken away in order to illustrate the interior. Fig. 5 is a transverse sectional elevation of a portion of the apparatus on the line 5-5 of Fig. 4. Fig. 6 is a sectional plan view of a portion of the device, drawn to a somewhat enlarged scale. Fig. 7 is a view in the nature of a diagram, illustrating the wiring connections between the pool-table and the recording apparatus. Fig. 8 is a face view of a portion of the record-strip. Fig. 9 is a view of the reverse side of the record-strip. Fig. 10 is a sectional plan view of a further modification of the invention, illustrating the mechanism by which the register is actuated mechanically. Fig. 11 is an end view of the same, portions of the apparatus being shown in section. Fig. 12 is a detail view of a portion of the mechanism for permitting rearward movement of the rheostat arm.

Similar characters of reference are employed to indicate corresponding parts throughout the several figures of the drawings.

- In some pool-tables of modern construction the balls after being forced in to the pockets automatically roll along runways under the table to suitable receptacles, the receptacles being provided each with an independent cover or lid, any one of which may be opened in order to allow the pocketed balls to enter, so that the balls of each player may be kept separate.
- 10 In the present instance the table 1 is provided with the usual six pockets, and the pocketed balls roll along runways 2 under the table to a channel 3, formed at one end of the table. The bottom of this channel is 15 formed of a plurality of doors 4, which in the present instance are pivoted, and said doors are connected, by means of tension-rods 5, with push-buttons 6, disposed at convenient points, preferably at the ends of the table, 20 there being a push-button for each of the doors, so that any one door may be opened, and an additional push-button which when depressed will close all of the doors, so that a scratch ball which may be driven into a 25 pocket will be received in the channel 3 formed by the doors and will not be allowed to enter any of the receptacles. Below the doors are arranged a pair of ball-receptacles 7, each provided with a handle 8, and each of 30 these receptacles is in the present instance divided into two compartments, there being four compartments in all, or the number of compartments may be increased in order to accommodate any number of players, and instead of employing two or more receptacles 35 the compartments may all be arranged within a single frame.

In playing the game No. 1 player depresses No. 1 button and forces open the door of No. 40 1 compartment. All of the balls pocketed by this player will roll along runways and will enter No. 1 compartment and in so doing will move past and depress a projecting arm 9, extending within the compartment, 45 and from movement of this arm the recording device will be operated. When No. 1 player fails, No. 2 player will depress No. 2 push-button and will open No. 2 door and will close the door of No. 1 compartment. 50 All of the balls pocketed by No. 2 will then roll into No. 2 compartment and will then move past and depress a similar projecting arm 9 in No. 2 compartment and will thus operate the recording mechanism and print a 55 record of the entry of the ball or balls in No. 2 compartment. In similar manner the balls of No. 3 player are received in No. 3 compartment and duly recorded. At the end of the game the receptacle or receptacles 8 are removed and the balls emptied out in the triangle and "set up" for another game. The removal of the receptacle or receptacles will make a printed record of the fact that a game has been played, and this printed record will 65 occur in the column of the player who has

pocketed the lowest number of balls, showing that such person has lost the game and owes the amount due.

Inasmuch as the apparatus forming the subject of the present invention may be used 70 in connection with a number of automatic "racking" devices, it has not been considered necessary to enter further into details of construction of the table and the ball receptacles or racks. A detailed description of the 75 construction of the table and ball-racks illustrated in the accompanying drawings will be found in Letters Patent of the United States No. 728,706, dated May 19, 1903.

In pool-rooms it is found necessary in 80 many cases to employ a separate attendant or marker for each table to keep track of the game, to rack the balls pocketed by each player, to announce the loser of the game, and to set up the balls at the completion of 85 the game. This is not only expensive, but in many cases it is found impossible to keep a proper check on the attendant, especially in the absence of the proprietor or cashier.

In carrying out the present invention it 90 has been found possible to provide means whereby a printed record will be kept of the number of balls pocketed by each player and to print in the column of the player pocketing the lowest number of balls the amount 95 due for the game, making it impossible for the balls to be set up and a game or games played without making a record of the fact, and, further, this record-strip, which serves as a bill, is in itself of such character that no 100 portion of it can be torn off or destroyed without the knowledge of the proprietor or cashier, so that after once setting the device for operation the table requires no further attention and a single marker may attend to a 105 dozen or more tables.

In the following description reference is made throughout to a recording device which may make a printed record; but it is to be understood that parts of the mechanism are 110 adapted for use in connection with a registering mechanism—such mechanism, for instance, as is employed for a total-register in ordinary cash-registering mechanism—and it may in some cases be found advantageous 115 to use merely a registering device instead of making a printed record.

The recording devices may be operated either by direct mechanical connection with the arm 9, or said arm 9 may be utilized for 120 the purpose of closing an electric circuit through electromagnets or similar devices arranged in a casing at any convenient distance on the table, said electromagnets operating the imprinting mechanism and serving to 125 feed the record-strip. When operated wholly by electricity, the parts are arranged within a suitable casing 20, which may be placed on the wall or at any other convenient point adjacent to the table, or it may be placed at the 130

cashier's desk. Arranged within the casing is a paper-roll 21, on which is wound a record-strip *x*, said strip being led up past the imprinting mechanism and between two rolls 22 and 23, while the end of the strip projects out through the slot 24 at the front of the casing, one of the edges of the slot having a knife-edge for convenience in tearing off a portion of the strip. The strip is of any desired width and may be ruled in parallel columns in the direction of its length, four of such columns being shown in the present instance, and these are exposed at an opening 25 in the front of the casing, so that, if necessary, the initials or names of the players may be inserted in the different columns in the order in which the game is to proceed.

The record which it is desired to make is shown in Fig. 8, on reference to which it will be seen that player A has made one ball, after which the strip has been advanced one step, that player B has made two balls, with an advance of two steps, that player C has made one ball, and so on until at the conclusion of the game players A and D have each made five balls, player B has made four balls, and player C has made only one ball, and being the loser, the amount due, twenty cents, is printed in the C column, thus showing that C is indebted to the extent of twenty cents. In similar manner the record of any number of games may be made and the amount printed in the column of the losing player. Provision is also made for adjusting the device, so that if three players only are engaged in a game "15" will be printed in the column of the losing player, or if only two players are engaged "10" will be printed. The record-strip is gradually fed out at the front of the casing, and it may be torn off at one end of each game or at the end of a series of games. In order to provide for the removal of a portion of the strip, the back of the strip has printed thereon numerals or other symbols, either in regular or predetermined order, and the sections of the strip may be pieced together at the cashier's desk, so that if any portion of the strip is missing the cashier will be notified.

Extending across the casing is a horizontally-disposed platform 28, and on said platform in front of each of the columns is arranged an electromagnet, preferably in the form of a solenoid 29, and each of these is connected in an independent circuit 30 to terminals in the path of movement of the ball entering one of the compartments, the terminals in the present instance being the arm 9 and a small contact-button 31. One end of the core 32 of the solenoid is connected to one arm of a bell-crank lever 33, that is mounted on a pivot-stud carried by the platform, and the opposite arm of said bell-crank lever is connected to a type-bar 34, mounted in a suitable guideway formed

in a block 35, carried by the platform. This type-bar is thrust forward when the magnet is energized and forces a carbon strip or inked ribbon 36 into engagement with the record-strip, the latter being forced back against a suitable platen 36', and the character thus printed may be in the form of a dot or dash, or it may be a numeral, letter, or other symbol. The platen 36' is mounted on two rocker-arms 37, carried by a rock-shaft 38, adapted to suitable bearings in the frame, and at one end of the rock-shaft is an arm 39, that is engaged by a spring 40, said spring tending to move the platen in the direction of the paper; but excessive movement in this direction is prevented by suitable stops 40', projecting inward from the opposite ends of the casing. To the rocker-arm 39 is pivoted a pawl-bar 41, normally held in engagement with the teeth of the ratchet-wheel 42 by movement of the spring 43, and at each depression of the type-bar the platen will be forced to the rear by said type-bars for a distance sufficient to lower the pawl-bar to the extent of one or more teeth. When the circuit is broken, the type-bar is retracted by spring 45 and the platen is returned to its initial position by the spring 40, and at the same time the pawl-bar 41 is moved up and turns the ratchet-wheel and the feed-roller 23, effecting the feeding movement of the record-strip, and this occurs immediately after each imprinting operation.

At a point adjacent to each of the electromagnets 29 is a rheostat 47, having a plurality of contacts 48 arranged in an arcuate row and provided in the usual manner with small resistance-coils. The rheostat-frame supports a horizontal shaft 49, on which is a small ratchet-wheel 50 and a circuit-closing arm 51, the end of which engages the contacts 48. The ratchet-wheel 50 is engaged by a pawl 52, pivoted to the solenoid-core 32, and the construction is such that each time the magnet is energized the pawl 52 will turn the ratchet-wheel to the extent of a single tooth and the contact-arm 51 will be advanced a single step and will cut in more and more resistance in a circuit which controls the printing of the amount in the column of the losing player.

The casing is provided with bearings for a horizontally-disposed shaft 54, that extends from end to end of the casing, projecting through one of the walls thereof and being provided with an enlarged knob 55, having a milled or knurled periphery and carrying a pointer 56, which may be moved over a dial 57, on which are numerals "5," "10," "15," and "20," indicating the several amounts which the games may cost, so that if two players are engaged the attendant or proprietor will turn the knob or pointer until the knob is opposite "10," or to "15" if three players are engaged, and this may be in-

creased to any extent, so as to provide for the playing of a game by any number of persons. On the shaft 54 are arranged a number of type-disks 58, bearing type for the printing of "5," "10," "15," and "20," and these are disposed in proper relative positions, so that any one of said type may be brought opposite the record-strip. In the present instance four type-disks are used, one of which is opposite each of the parallel columns of the strip, and all are turned so that all of the fives or all of the tens, fifteen, or twenties will be opposite the strip at the same time. The casing is further provided with a horizontal shelf 60, carrying a plurality of brackets 61, and on each bracket is an electromagnet 62. In front of the electromagnets is an armature 63, pivoted to the bracket and having its upper end bent into a horizontal plane to form an impression-hammer 64, the surface of which is directly opposite and in a horizontal plane with the axis of the shaft 54. One of these impression-hammers and magnets is placed opposite the type-disks, and at the completion of the game one of these electromagnets will be energized, and by attracting its armature the proper impression-hammer will be moved forward against the paper and the latter will press against the inked ribbon and force the latter against the selected type of the disk 58 and will print in the proper column the amount due for the game played, and this amount will be strictly in accordance with the adjustment of the pointer 56, which is moved to proper position before the starting of the game and readjusted when a player enters or leaves the game.

At the lower portion of the ball-receptacle is arranged a circuit-closer 65, comprising a stationary contact and a movable spring-pressed contact, that is engaged by the receptacle when the latter is in position and is held with the circuit broken. When the ball-receptacle is removed for the purpose of rearranging the balls in the table at the starting of a fresh game, the circuit-closer will move to close a circuit which extends to each of the rheostats and electromagnets 62. Each of the rheostats is connected in series with one of the electromagnets by a wire 66, and the amount of resistance in this circuit is determined by the extent of movement of the contact-arm 51, so that if the movement is but small, as in the case of a player making one ball, there will be but very little resistance in the circuit. If the player has pocketed a large number of balls, the resistance will be proportionately increased. Each of the rheostat-circuits is connected in multiple with the circuit 67, which includes a circuit-closer 65 and a battery 68. As the game progresses the balls pocketed by the several players will effect movement of the arm 51 in the manner previously described and the re-

sistance in the circuit will be increased in proportion to the number of balls gained. When the game has been finished, the removal of the ball-receptacle from the end of the table will close the circuit 67 and all of the several rheostat-circuits will be connected in multiple with the battery. The electromagnets 62 have very low resistance, and only that one connected in the circuit of least resistance will be energized, and the energizing of the proper electromagnet 62 will cause movement of the armature and force the impression-hammer 64 toward the paper and print the amount due in the column of the player having the lowest number of balls.

In the event of a player making a scratch, which will necessitate the return of one or more balls from the ball-rack to the table, provision is made for recording the fact on the record-strip and at the same time permitting rearward movement of the switch-arm, so that the amount of resistance cut in will always be strictly in proportion to the number of balls which are in the compartment and not the number of balls which have been pocketed, so that at the end of the game the record will accurately show the number of balls which each player actually has and the resistance of each circuit will be properly proportioned in accordance with the number of balls. In the front wall of each of the compartments is an opening through which single balls may be removed in order to pay for scratches. At the inside of each opening is a spring-pressed bar 70, that may be engaged by a ball as it is withdrawn from the opening in the ball-receptacle. This bar is provided with a pair of contacts 71 and 72, either of which may be brought into engagement with pairs of contacts 73 and 74, connected by current-conducting wires 75 to spring-mounted rods 76, held in suitable guides at the rear of the removable receptacle. The rods 76 are formed each in two pieces, and the pieces are insulated from each other. These come into engagement with pairs of contacts 77, that are carried by the stationary frame of the pool-table, and the arrangement of the parts is such that each time a ball is removed through the opening and engages a rod 70 it will close one of the circuits, and these, with suitable mechanism, will make a record of the fact that a ball has been removed from the rack or receptacle, the record being made in the column of the player who has made the scratch.

To the under side of the platform 20 are secured electromagnets 78, one for each player, and the movement of the cores 79 of said electromagnets is transmitted to a pivotally-mounted type-bar 80, carrying suitable type for imprinting a cross or other distinguishing-mark on the record-strip each time the circuit is closed. Each magnet is connected to

one of the sets of circuit-closers by wires 81. To the opposite end of the core is connected a lever 82, one end of which is adapted to engage the pawl 52 and raise the same from engagement with the ratchet-wheel 50. The under side of the pawl 52 is reduced in width, and the end of the lever 82 is provided with a pivoted toe 83, adapted to engage with the pawl. The toe is pivoted in such manner as to engage with and elevate the pawl during operative movement and during return movement, when the magnet is deenergized, will slide under the pawl without raising the same. The lever 82 further carries a tooth 84, so positioned that it will normally be in a line about midway of the radial face of the teeth of the ratchet-wheel 50. In the operation of this portion of the mechanism the energizing of the electromagnet will cause the core to move, and lever 82 will be turned on its pivot until the tooth 84 moves to a position where it will engage the teeth of the ratchet-wheel. During this movement the toe 83 engages with and raises the pawl 52, and the teeth of the ratchet-wheel will then be moved backward by means of a small spring 85; but the backward movement will be stopped by the engagement of one of the teeth of the ratchet-wheel with the tooth 84. The raising of the pawl 52 is but momentary, and it may immediately fall again on top of the ratchet-teeth; but its active face is about midway between the edges of the teeth, and it is only after the tooth 84 has moved out of engagement with the ratchet-wheel that the latter is again revolved in the reverse direction, and the operation is completed when the next tooth comes into engagement with the pawl 52, the whole of the reverse movement of the ratchet-wheel being to the extent of a single tooth or equivalent to the value of a single ball, and this will occur each time a ball is moved from the rack. It will further be observed that this rearward movement will also cut out a proportionate amount of the resistance, so that the resistance of each rheostat will be strictly in proportion to the number of balls which are retained in the player's rack or receptacle and not the total amount of balls pocketed. The toe 83 is so disposed as to normally engage the ratchet-wheel, and thus may serve as a holding-pawl for retaining the ratchet-wheel in position during the operation of the electromagnet 29.

In order to provide for the return of all of the parts to initial position, as well as to feed the paper after the imprinting of the amount due for the game, an electromagnet 94 is placed at one side of the casing and is provided with a movable core 95, carrying a pawl 96 for engagement with the teeth of the ratchet-wheel 42, and said pawl and core are retracted by a spring 97. This electromagnet is connected in a local circuit 98, of which the terminals 99 are disposed in the path of

movement of the lower ends of the armature-levers 63, and the wiring is so arranged that the movement of any one of the armatures 63 will close said local circuit, and when closed the electromagnet 94 will be energized and 70 its core will be forced upward until pawl 96 engages a fresh tooth of the ratchet-wheel. When the circuit is broken after the completion of the printing operation, the pawl is retracted by its spring and the paper-feeding 75 roll is turned in order to feed the paper up. The core 95 is adapted to engage with one arm of a bell-crank lever 100, the opposite arm of which is in engagement with one arm of a rocker-arm 101. This rocker-arm is connected to a rock-shaft 102, carrying four rocker-arms 103, disposed one in the path of each of the pawls 52, and in the operation of this portion of the mechanism the retraction of the core 95 will force the lower arm of the bell-crank lever 100 downward and depress the rocker-arm 101, causing the shaft 102 to rock and raise all of the arms 103, so that the pawls 52 will be elevated from engagement with the ratchet-teeth 50, and thereupon the spring 85 connected to said ratchet-wheels will restore them to their initial position. The engagement of the bell-crank lever 100 with the rocker-arm 101 is but momentary, and the engaging arm immediately wipes past the 90 rocker-arm, so that the weight of the pawl will be sufficient to again restore them to their initial positions after the springs have restored the ratchet-wheels and the circuit-closing arms to initial position. The upper 100 arm of the bell-crank lever 100 is slotted and is connected to the core 95 by a pin, so that the core-bar will move the lever in both directions and permit to some extent free movement of the bell-crank lever and allow it to go to initial position; there being sufficient give or spring of the parts at this point to permit them to reassume initial position after each operation. Should there be a tie game between two or more of the players, the resistance offered by each of the rheostats will be the same, and in that case the current will divide and the amount due will be printed in each of the columns having the lowest number of balls, thus indicating that the amount 115 is due partly from each of the players in whose column the amount is printed.

In some cases it may be desired to arrange the recording mechanism directly on the table, and in such cases the mechanism may be made to operate by direct mechanical connection with the arms 9, or the operation may be accomplished partly by mechanical means and partly by the aid of electromagnets.

At a point to the rear of the ball-receptacles are bearings for the support of a plurality of concentric shafts 104, 105, 106, and 107, each of said shafts being independently operable and each carrying a plurality of arms 108, that project within the ball-recep- 125 130

tacles. In the present instance four arms are shown on each of the shafts, and these are so arranged and disposed as to be successively operated by balls passing into the receptacle, 5 the balls turning the shaft to the extent of ninety degrees at each operation and the movement being such as to present a fresh arm in position to be engaged by a succeeding ball. The opposite ends of the shafts extend into a suitable casing 109, that is secured to the table, and each shaft carries a pinion 110. The pinions engage gears 111, that are mounted loosely on a shaft or arbor 112, the shaft being rigidly held in place 15 within the casing. To each gear-wheel 111 is secured a type-disk 112' and a recessed stop-wheel 113, with which engages a spring-pressed locking-pin 114. The type-disk has on its periphery imprinting-type 20 ranging from "0" to "15," and these may be brought successively into alinement with an impression-hammer 115. Each ball as it drops into the receptacle turns the pinion 110 to the extent of ninety degrees, and this 25 movement transmitted to the gear-wheel 111 turns the type-disk to the extent of a single imprinting-type, so that the type are brought successively opposite the impression-hammer 115. During this operation the spring- 30 pressed pin 114 is forced downward, and it clicks into the successive recesses and holds the type-disk in the position to which it is adjusted. The impression-hammer is sufficiently wide to present an impression-surface 35 opposite all of the type-disks, and said hammer is carried by a pair of pivotally-mounted levers 116, to one of which is connected a toothed bar 117. The tooth at the end of this bar is in engagement with a stationary tooth 119 on the ball-receptacle, and in said ball-receptacle is a recess 120, having an inclined face for engagement with a similarly-inclined face of the toothed bar. At the completion of a game the ball-receptacle 40 is removed and the tooth 119 engages the toothed bar 117, pulls the latter outward, and forces the impression-hammer 115 into engagement with a strip of paper *y*, on front of which is an inked ribbon *z*. The ribbon is 45 forced into contact with the type, and the impression shows in a single line the number of balls which have been dropped into the various receptacles. The outward movement of the ball-receptacle engages the tooth 119 50 with the tooth at the end of the bar 117, and the latter is pulled outward to an extent sufficient for this purpose. The toothed end of the bar 117 is inclined, and during its outward movement the inclined face rides against the 55 inclined wall of a notch 120, and the end of the arm is gradually moved away from the tooth 119, and the hammer is then free to return to its initial position under the influence of spring 122. The printed strip containing the record at the end of the game 60

may then be drawn out of the casing and may be torn off to show the result of the game. One of the teeth of the stop-wheel 113 is elongated, as illustrated at 123, and the several disks are connected to spiral 70 springs 124, which are wound during the registering or recording operation. Each pin 114 is mounted in a guide-bar 126 and is provided with a recess 127, the lower shoulder or wall of which may at times engage with the 75 upper surface of the guiding-bar 126 and maintain the stop-pin in its lowest position. Normally, however, the pin will be held up by a spring 128. Connected to the stop-pin is a spring 129, which when the pin is fully 80 depressed will draw the pin sidewise in such manner that the lower wall of the recess will engage the bar 126 and hold said pin depressed. This is accomplished by means of a bell-crank lever 130, pivoted to the bar and 85 having two arms, of which the substantially horizontal arm is adapted to engage a pin 131 on the stop-pin. The substantially vertical arm of the bell-crank lever is arranged under a bar 132 and is engaged by a depending cam 90 133 on a rod 134, carried by the arm 116, there being one of such rods 134 for each of the disks. During the outward or imprinting movement cam 133 passes over the bell-crank lever, and the horizontal arm of the 95 latter is raised without in any manner affecting the position of the pin. In the reverse movement of the impression-hammer the cam will move the vertical arm of the bell-crank lever, and its horizontal arm will be depressed into engagement with the pin 131 and will force said pin downward until the 100 spring is free to move the shoulder of the recess 127 to engage under the bar 126. This may release all of the type-disks, and the latter 105 are free to return to their initial positions under the influence of the springs. As each of the type-disks is turned to its initial position the elongated tooth 123 will come into engagement with the stop-pin and will force 110 the same in the direction of the impression-hammer until the shoulder of the recess is disengaged from the bar 126, whereupon the spring 128 will force the stop-pin into engagement with the first tooth of the ratchet-wheel and the parts will be in readiness for 115 another operation.

Having thus described the invention, what is claimed is—

1. In a pool-game recorder, the combination with independent receptacles in which the balls are received and retained, of an independent printing mechanism for each receptacle, and means for automatically operating said printing mechanism on the pocketing of each ball. 120

2. In combination with receptacles for pool-balls, of means for making a separate record of the number of balls entering and retained in each receptacle. 130

3. The combination with separate receptacles for the balls pocketed by different players, of means for recording the number of balls entering and removed from each receptacle, said records being printed in independent parallel columns. 65
4. The combination with separate receptacles for the balls of different players, of means for indicating the number of balls entering and removed from each receptacle. 70
5. The combination with a plurality of ball-receptacles, of independent recording means for each receptacle, and automatic mechanism for imprinting the charge for the game in the column in which the lowest number of balls is recorded. 75
6. The combination with a pool-table, of means for keeping a record of the balls pocketed by each player, and automatic mechanism for recording the charge for each game in the column recording the lowest number of balls. 80
7. The combination with a pool-table, having a plurality of receptacles for the balls pocketed by different players, of a ball-operated means for automatically recording in separate columns the number of balls pocketed by each player, and ball-operated means for recording in said columns the number of balls removed from the receptacles. 85
8. The combination with a pool-table, a ball-operated imprinting mechanism for keeping separate records of the balls pocketed by each player, and means for automatically imprinting the charge for each game in alinement with the record of the lowest number of balls. 90
9. The combination with a pool-table, of a plurality of ball-receiving compartments, and means for recording the number of balls entering and retained in each compartment. 95
10. In recording mechanism, means for making independent records in separate columns, and automatic mechanism for imprinting a distinguishing-mark in the column having the smallest record. 100
11. In recording mechanism for pool-tables, means for automatically registering in independent columns the number of balls made by the individual players, and means for automatically printing in one of the columns the amount due for each game. 105
12. In recording mechanisms, means for keeping independent records in different columns, a plurality of mechanisms arranged for the printing of predetermined characters, one of said printing means being located opposite each column, and means controlled by the independent recording means for automatically selecting the printing means to be operated. 110
13. The combination with recording means, for keeping independent records in independent columns, of an automatically-selected printing means controlled by the independent recording means for printing a predetermined character in one of them. 115
14. In a recorder, means for maintaining independent records in independent columns, and an adjustable imprinting means controlled by the independent recording means for printing a distinguishing character in one of such columns. 120
15. In combination with means for maintaining independent records in independent columns, of an adjustable means for printing a distinguishing character in one of them, and means controlled by the independent recording means for automatically determining the column in which such character is to be printed. 125
16. The combination with means for keeping independent records in independent columns, of a plurality of type-disks arranged one opposite each column and bearing type representing different values, and means controllable by the independent recording means for determining the operative type-disk. 130
17. The combination with means for keeping independent records in independent columns, of a plurality of type-disks each bearing type representing different values and a selecting means controllable by the independent recording devices for determining the operative type-disks. 135
18. The combination with means for maintaining independent records in independent columns, of a plurality of type-disks bearing numerals of different values; said disks being simultaneously adjustable to present any of the type to imprinting position and means controllable by the independent recording devices for determining the operative type-disk. 140
19. The combination with a platen, of means for printing independent records in independent columns, a plurality of type-disks bearing numerals of different values, the said disks being simultaneously adjustable to present any one set of numerals in alinement with the platen, and a selecting means controllable by the independent recording means for operating the type-disk opposite the recording mechanism which has been operated the fewest number of times. 145
20. The combination with means for maintaining independent records in independent columns, of a rheostat for each of such mechanisms, means controlled by said mechanisms for cutting in resistance to an extent proportionate to the number of operations of the recording mechanisms, type-disks for printing the final distinguishing character in one of the columns and an imprinting means coacting with said type and including an electromagnet and a circuit connecting such electromagnet to all of the rheostats. 150

21. The combination with a plurality of electromagnets arranged in independent circuits, an imprinting device for each electromagnet, a rheostat arranged in connection with each electromagnet, a contact-arm forming a part of the rheostat and operable by the electromagnet to successively cut in resistance each time the mechanism is operated, a plurality of final imprinting mechanisms, independent electromagnets for actuating them, and a circuit including the rheostats, the second set of magnets and a source of electrical energy.

22. The combination with a series of electromagnets, of an imprinting device for each electromagnet, a rheostat, a contact-arm forming a part of the rheostat, and operable by the electromagnet to successively cut in resistance in proportion to the number of times the electromagnet is energized, there being one of such imprinting mechanisms and rheostats for each of the electromagnets, a second series of electromagnets each serially connected with one of the rheostats, and an electric circuit having multiple connection with the several series circuits.

23. The combination of a plurality of independent electromagnets arranged in ball-operated circuits, of an imprinting mechanism for each electromagnet, a rheostat associated with each electromagnet, a ratchet-wheel and operating-pawl connected to the armature of the electromagnet, a rheostat contact-arm movable with the ratchet-wheel and operating to successively cut in resistance in proportion to the number of operations of the electromagnets, and means controllable by a scratch-ball for temporarily releasing the pawl and permitting reverse movement of the wheel and contact-arm.

24. The combination with a plurality of independent electromagnets arranged in ball-controlled circuits, a ball-receptacle, an imprinting mechanism operable by each of the electromagnets, a rheostat associated with each electromagnet, a rheostat contact-arm, a ratchet-wheel connected thereto, a pawl connected to the armature of the electromagnet, and engaging said ratchet-wheel, a spring tending to restore the ratchet-wheel to initial position, a second set of energized electromagnets, an imprinting mechanism for each of the second set of electromagnets, the circuits of said second set of electromagnets being controlled by balls removed from the receptacle, and means operable by said second set of electromagnets for raising the pawls and permitting reverse movement of the ratchet-wheel and contact-arms of each receptacle each time a ball is removed from said receptacle.

25. The combination with a ball-receptacle, of a plurality of independent electromagnets arranged in ball-controlled circuits,

an imprinting mechanism for each electromagnet, a rheostat associated with each electromagnet, a rheostat contact-arm for successively cutting in resistance each time the electromagnet is energized, a ratchet-wheel carrying said contact-arm, a spring tending to reverse the movement of the ratchet-wheel, a pawl engaging the ratchet-wheel and connected to the armature of the electromagnet, a second set of electromagnets, independent circuits in which said electromagnets are arranged, said independent circuits being controllable by the removal of balls from the receptacle, an imprinting mechanism for each of the second set of electromagnets and an escapement mechanism controllable by said second set of electromagnets for releasing the pawl and permitting reverse movement of the ratchet-wheel and contact-arm of each receptacle each time a ball is removed from the receptacle.

26. The combination with a ball-receptacle, of a plurality of electromagnets connected in independent ball-controlled circuits, an imprinting mechanism for each electromagnet, a rheostat associated with each electromagnet, a rheostat contact-arm for successively cutting in resistance each time the electromagnet is energized, a ratchet-wheel carrying said contact-arm, a pawl engaging the ratchet-wheel and operable by the electromagnet, a second set of electromagnets, imprinting-type operable thereby for printing in a selected column a mark or symbol designating the loser of the game, said electromagnets being each connected in series with one of the rheostats, an electric circuit having a multiple connection with the series circuits, and an auxiliary circuit controlled on the final imprinting means for raising all of the pawls and permitting movement of the parts to initial position.

27. The combination with a pool-table, of a series of independent ball-receptacles, a plurality of concentric shafts, projecting arms carried by the shaft and extending into the receptacles in the path of the balls, type-disks connected one to each of the shafts and receiving movement on the entrance of each ball, and an imprinting means operable on the removal of the balls to imprint the number of balls remaining in each receptacle.

28. The combination with a pool-table, of a series of independent receptacles, a plurality of concentric shafts, radial arms extending from the shaft and projecting into the receptacles in the path of the entering balls, pinions secured to the shaft, independent gears one in mesh with each pinion, type-disks carried by the gears, a stop-wheel having a plurality of peripheral recesses, one of such stop-wheels being connected to each type-disk, springs for restoring the type-disks to initial position, pins for entering the

recesses of the stop-wheels, and an elongated tooth carried by each of the stop-wheels for engaging said pin, an impression-hammer operable on the movement of the receptacle for printing a record of the position of the type-disks at the conclusion of the game, and means operable by movement of the impression-hammer for moving the pins outward from engagement with the stop-wheels.

5   In testimony that we claim the foregoing

as our own we have hereto affixed our signatures in the presence of two witnesses.

GEORGE FRANK GOSS.
JOHN E. PARKER.
